FLUID-OPERATED PRESS

Robert Alexander Cuthbert, High Wycombe, England, assignor to Broom and Wade Limited, High Wycombe, England, a British company

Application May 27, 1942, Serial No. 444,724
In Great Britain June 5, 1941

18 Claims. (Cl. 60—97)

This invention relates to power presses for performing any desired particular operation such for example as riveting, punching, shearing, actual pressing or otherwise, of the type in which the press includes a power piston working in a power cylinder to actuate a piston rod or ram which transmits the actual force to perform the necessary work, the press being operated by a liquid under a high working pressure (such as supplied from an intensifier), and has for its main object to provide such devices of an extremely efficient and simple form.

As is well known, in the majority of presses it is not necessary for the power piston and its rod, ram or the like to transmit a high working force throughout the whole of its stroke, but it is sufficient if the maximum force is exerted for a desired proportion of the stroke at its conclusion; in other words, the total stroke can be divided into what may be termed the "approach" portion (requiring but slight force) and the "working" portion (requiring the full force).

The present invention has for its object to provide means by which the power piston and parts connected therewith can be moved for the "approach" portion of the stroke without the pressure liquid acting upon the power piston for the purpose, the said pressure liquid then acting upon the power piston to carry out the "working" portion of the stroke.

In general, presses in accordance with the invention are provided with a subsidiary cylinder of smaller diameter than the power cylinder in which works a subsidiary piston directly or indirectly connected with the power piston and its rod, ram or the like, the arrangement being such that the "approach" portion of the stroke is effected by the pressure liquid acting upon the subsidiary piston to move it and the power piston, and the construction including automatically operated valve means whereby when the "approach" portion of the stroke is effected the pressure liquid is caused to act upon the working face of the power piston for the performance of the "working" portion of the stroke.

The automatically operated valve means can have various constructions and be operated in accordance therewith. In most forms, however, in the mechanism extending from the subsidiary piston to the main piston rod or ram there is included a connection between the operating parts having the capacity of permitting a slight movement. Spring means normally keep the parts of the connection pressed to one extreme position, but when the "approach" portion of the

stroke terminates then the continued pressure of the pressure liquid on the subsidiary piston causes the parts to move to the other extreme position and by this slight movement, a suitable part or parts effect the opening of a valve to allow the pressure liquid to pass to the power cylinder and operate upon the working face of the power piston. When the "working" portion of the stroke has been effected, upon the return of the parts this spring acts to bring the parts of the connection into their original position.

Preferably the construction is such that the power cylinder is filled on both sides of the power piston with the working liquid, a passage or passages being provided through the power piston or from end to end of the power cylinder to enable the said liquid to pass from side to side of the power piston during the "approach" portion of the stroke, but having means combined therewith whereby when the "approach" portion is effected, for closing the said passage or passages, so that the pressure liquid can act upon the power piston to effect the "working" portion of the stroke. The means for closing the said passage or passages preferably is caused to operate in an automatic manner by the same means as that which opens the valve for supplying the liquid under pressure to act upon the power piston.

Additionally and by preference, a reservoir or compensating chamber may also be provided for the working liquid in connection with the power cylinder. This suitably communicates with the power cylinder and by preference on the side remote from that in which the working face of the power piston forms a boundary.

As will be realised, many constructions may be adopted for carrying the invention into effect and presses in accordance with the invention may be fixed or portable, in any case, especially the latter case, if desired the intensifier being separate from the press proper.

In order that the invention may be better understood it will now be described with reference to the accompanying drawing, which is given by way of example only and in which—

Fig. 1 shows in elevation one structural method of carrying the invention into effect, partly in section with the power piston at the upper end of its stroke.

Fig. 2 shows a fragmentary portion of Fig. 1, but with the power piston in the position just after the commencement of the power stroke and some parts shown in modified form.

In the drawing, 3 is the power cylinder having one integral closed end 4 which is apertured

to receive in a close fitting manner a supplementary cylinder 5 having a positioning flange 6 coming on the interior of the end 4. The other end of the power cylinder is screw-threaded for the reception of a detachable end member 7 having an extension 8 screw-threaded on the exterior, the extension forming a guideway for the piston rod 9; the end member also has a plugged filling aperture 10 guarded by a one way valve. The screw-threaded extension 8 receives a correspondingly threaded bore of one arm of a yoke 11 of any usual construction, the parts being held in position by a locknut 12. The other arm of the yoke carries one of the dies or the like 13, the other die 14 being carried on the end of the piston rod 9.

The cylinder 3 has an exterior jacket 15 thereon which abuts a flange 16 at one end with the interposition of suitable packing. The other end extends beyond the end 4 of the cylinder 3 and abuts a clamping plate 17 with the interposition of packing forming the exterior flange of an air-filled rubber cushion 18 of hollow annular V-shaped section.

A thrust sleeve 19 also comes around a portion of the subsidiary cylinder 5 to abut at one of its ends with suitable packing the end 4 of the cylinder 3, and at the other end the interior flange of the cushion 18.

The plate 17 is apertured and held on the cylinder 5 by a nut 20 in screw-threaded engagement with a screw-threaded portion on the end of the cylinder 5 which projects through the said plate 17.

By the shape and construction of the parts a space 21 is left between the exterior of the cushion 18, a portion of the interior of the jacket 15 and the outer surface of the end 4, which space constitutes a liquid reservoir. The exterior of the cylinder 3 has between itself and the interior surface of the jacket 15 a number of passageways 22 which communicate on the one hand by conduits 23 with the space 21 and on the other hand through apertures 24 with the interior of the cylinder 3.

25 is the power piston working in the cylinder 3, which is not connected directly to the piston rod 9 but through the following mechanism. Secured to its rear is a sleeve 26 by means of a flange, this sleeve on the interior having two diameters. The larger diameter is in the portion adjacent the piston 25 and is a close sliding fit on an enlarged portion 27 on the end of the piston rod 9. The smaller diameter portion is in the nature of a flange 28 the interior diameter of which is a close sliding fit on the piston rod 9, the step between the two diameters of the piston rod forming a limiting abutment for the flange 28. The enlarged portion 27 has a recess 27a therein and between this recess and another recess 29 at the rear of the piston 25 is located a compression spring 30 of suitable strength. The arrangement is such that normally there is a certain distance between the actual end 31 of the enlarged portion 27 and the actual surface 32 at the rear of the piston 25. In certain conditions, however, these surfaces come into contact. When held separate by the spring action 30, the space between the surfaces 31 and 32 communicates with the interior of the cylinder 3 below the piston 25, by means of apertures 33 in the sleeve 26. The arrangement between the parts, however, is such that these apertures are closed by the exterior surface of the enlargement 27 when

the piston 25 contacts by its surface 32 with the surface 31 of the enlargement 27 (Fig. 2).

The subsidiary cylinder 5 has working therein a subsidiary piston 34 which is formed hollow and at its front has a stepped flange 35 secured by suitable screws to the piston 25. The flange 35 has apertures 36 therein. The piston 34 has fixed therein an inner tubular member 37 terminating towards the piston 25 at a desired distance therefrom in a notched seating 38. Further, the piston 34 at its front has a reduced stepped aperture, the upper portion 39 forming a seating for a ball 40 constituting a valve coming at the upper end of a projecting rod 41 secured concentrically in the enlarged portion 27 of the piston rod.

The recess 29 in the piston 25 opens to the front of the piston 25 through an annular passageway 42.

The whole arrangement is such that in the position shown in Fig. 1 communication exists between the two sides of the piston 25. That is to say, from the lower side the oil is free to pass through the aperture 33, the recess 29, the passageway 42 and the apertures 36 to the front of the piston.

When, however, the surfaces 31 and 32 are in contact (Fig. 2), then this passageway is closed and even before the surfaces 31 and 32 come into contact any passageway through the apertures 33 is closed.

In this position, however, the ball 40 is either closely adjacent or in contact with the notched seating 38. This does not prevent pressure liquid passing through the member 37 and the notches, to act upon the upper surface of the piston 25.

The complete action readily will be appreciated. When the pressure fluid is permitted to pass to the tool, by valve control from an intensifier or the like through the hollow piston 34, the parts are in the position shown in Fig. 1 and consequently the said fluid is precluded from acting upon the surface of the piston 25 as it cannot pass the ball valve 40. Consequently it acts upon the subsidiary piston 34 by exerting pressure on the tubular end thereof and upon the surface of the ball 40. This is sufficient to perform the "approach" portion of the stroke during which period oil with which the system is filled readily passes from the lower side to the upper side of the piston 25 and also from the lower portion of the cylinder 3 (through the passageways 23) to the reservoir 21.

When, however, the die 14 encounters its major resistance, then by continued action through the piston 34 and the piston 25, the sleeve 26 slides over the enlarged portion 27 and by its portion of smaller diameter 28, over the piston rod 9.

The result is, the surfaces 31 and 32 are brought together, closing the passage through the piston 25 for the oil and the ball valve 40 is removed from its seat 39. As a consequence, the oil coming from the intensifier passes through the hollow member 37 and the notched seating 38 to and through the apertures 36 in order to act upon the upper surface of the piston 25, and thus the pressure fluid exerts its effect through the large area of the said piston, to accomplish the purpose of the tool, such for example as riveting.

The return stroke is effected by a compression spring 43 on the under side of the piston 25, which surrounds the sleeve 26 and rod 9 and during this return stroke the requisite amount of oil which comes above the piston 25 is returned to the intensifier. Further, when the

pressure conditions are satisfied during the return stroke the spring 30 again separates the surfaces 31 and 32 to bring the parts into the position shown in Fig. 1.

As will be appreciated, the air-filled cushion 18 automatically compensates for the varied volume of comparatively incompressible fluid supplied to the space 21 during the action of the tool.

The upper portion of Fig. 2 indicates a variation of the structure for the air-filled cushion and shows two air-filled hollow rings 44, although only one such ring could be employed, or more than two, or in some cases such rings could be replaced by hollow balls, or otherwise.

Such a construction, however, modifies the arrangement for securing the clamping plate 17 into position and in the construction shown in Fig. 2 this plate 17 takes the form of a stepped plate having additional packing members co-operating with its outer and inner contacts with the structure.

In some cases the air-filled cushion on the interior of the press can be replaced by a freely sliding piston arrangement with or without a return spring, and further where required the reservoir for the fluid could be in a separate chamber fixed to the tool, for example at one side thereof, or separate therefrom.

Whatever form may be adopted, it will be understood that as the volume of the portion of the power cylinder behind the power piston decreases, pressure liquid therefrom automatically passes to the chamber or reservoir, the variation in volume of which is permitted by the air-filled cushion, spring-pressed piston, or otherwise.

It will be realised that the mechanism for operating the automatic valve means may be made in many other manners. For example, the power piston could be fixed to its piston rod or ram and spring means could be included between the end of the subsidiary piston and the power piston which, for the "approach" portion of the stroke would transmit the pressure from the subsidiary piston to the power piston but which would be compressed for the "working" portion of the stroke, during which compression the valve means provided would be opened to give free passage of the pressure liquid from the subsidiary cylinder to the power cylinder, to operate upon the working face of the power piston.

The invention is not limited to the precise forms or details of construction described, as these may be varied to suit particular requirements.

What I claim and desire to secure by Letters Patent of the United States of America is:

1. In a machine of the character described, the combination of a cylinder, a power piston in the cylinder, a tubular auxiliary piston fixedly connected with the power piston, a closure for the tubular piston, a conduit for admitting pressure fluid against said closure to impart movement to both of said pistons, and means on the power piston movable relatively thereto independent of the pressure of the pressure fluid and responsive solely to a predetermined value of resistance encountered against movement of said means for opening said closure and admitting the pressure fluid through said auxiliary tubular piston to the power piston.

2. In a machine of the character described, the combination of a cylinder, a power piston in the cylinder, a tubular auxiliary piston fixedly connected with the power piston, a closure for the tubular piston, and means movable relatively to

the power piston and responsive to impact of said means on a movement resisting element for opening the closure and admitting pressure fluid through the tubular auxiliary piston to the power piston.

3. In a machine of the character described, the combination of a cylinder, a power piston in the cylinder, a tubular auxiliary piston fixedly connected with the power piston, a closure for the auxiliary piston, and means supported by the power piston and movable relatively to the same and responsive to impact of said means on a movement resisting element for opening the closure and admitting pressure fluid through the tubular auxiliary piston to the power piston.

4. In a machine of the character described, the combination of a cylinder, a power piston in the cylinder, a tubular auxiliary piston fixedly connected with the power piston, a closure for the tubular piston, a tool supported by the power piston movable relatively thereto, and means responsive to impact of said tool on a movement resisting element for opening said closure and admitting the pressure fluid through the tubular auxiliary piston to the power piston.

5. In a machine of the character described, the combination of a cylinder, a power piston in the cylinder, a tubular auxiliary piston fixedly connected with the power piston, a closure for the tubular piston, a conduit for admitting pressure fluid against said closure to impart movement to both of said pistons, and means supported by the power piston and movable relatively to the same and responsive to impact of said means on a movement resisting element for opening said closure and admitting the pressure fluid through the tubular auxiliary piston to the power piston, said power piston, auxiliary piston, closure and impact responsive means forming a self-contained structure as such insertible into and removable from the cylinder.

6. In a machine of the character described, the combination of a cylinder containing pressure fluid, a power piston in the cylinder, a tubular auxiliary piston fixedly connected with the power piston, a closure for the tubular auxiliary piston, a conduit for admitting pressure fluid against said closure to impart movement to both of said pistons, and means on the power piston independent of the pressure fluid and responsive to impact on a movement resisting element for opening the closure and admitting the pressure fluid through the tubular auxiliary piston to one side of the power piston, the power piston having a passage therethrough controllable by the impact responsive means for the flow of the pressure fluid through said piston from the opposite side of the piston.

7. In a machine of the character described, the combination of a cylinder containing pressure fluid, a power piston movable in the cylinder, a tubular auxiliary piston fixedly connected to the power piston, a closure for said tubular auxiliary piston, a conduit for admitting pressure fluid to said cylinder, the closure being adapted to obstruct the flow of pressure fluid from said conduit into the cylinder, a tool supported by the power piston movable relatively thereto, and means responsive to impact of said tool on a movement resisting element for opening the closure and admitting the pressure fluid through said tubular auxiliary piston to one side of said power piston, the power piston and auxiliary piston having communicating passages therethrough which are controlled by said means to establish communica-

tion between both sides of the power piston and auxiliary piston connected thereto.

8. In a machine of the character described, the combination of a cylinder, a power piston movable in the cylinder, a tubular auxiliary piston fixedly connected with the power piston, a closure for the tubular piston, a conduit for admitting pressure fluid against said closure to impart movement to both of said pistons, a tool supported by the power piston movable relatively thereto and responsive to impact on a movement resisting element for opening the closure and admitting pressure fluid through the tubular auxiliary piston to the power piston, a passage through the power piston, said tool being adapted to obstruct the flow of fluid through said passage from one side of the piston to the other during a portion of its movement relative to the piston.

9. In a machine of the character described, the combination of a cylinder, a power piston movable in the cylinder, a tubular auxiliary piston fixedly connected with the power piston, a closure for the tubular piston, a conduit for admitting pressure fluid against said closure to impart movement to both of said pistons, a tool supported by the power piston movable relatively thereto, a fluid passage through the power piston, and means responsive to impact of said tool on a movement resisting element for obstructing said passage while permitting continued movement of said power piston relatively to said tool.

10. In a machine of the character described, the combination of a cylinder, a power piston movable in said cylinder, a tubular auxiliary piston fixedly connected with said power piston, a closure for said tubular auxiliary piston, a conduit for admitting pressure fluid against said closure to impart movement to both of said pistons, impact responsive means for opening said closure and establishing communication between said conduit and one side of the power piston, the cylinder containing pressure fluid on both sides of the power piston, a reservoir for pressure fluid outside said cylinder, a compressible element within said reservoir, and means for conveying pressure fluid forced by movement of the power piston in the cylinder from the latter into the reservoir against said compressible element.

11. In a machine of the character described, the combination of a cylinder containing fluid, a power piston movable in said cylinder, a tool supported by said power piston and movable relatively thereto upon impacting a movement resisting element, means for admitting pressure fluid into the cylinder upon encounter of the impact responsive tool to the movement resisting element, a reservoir, a compressible and expansible volume compensating element within said reservoir, means for conducting fluid forced from said cylinder into said reservoir and for compressing said compressible volume compensating element.

12. In a machine of the character described, the combination of a cylinder, a power piston movable in said cylinder against the action of pressure fluid contained in said cylinder, an impact responsive tool supported by said piston and movable relatively thereto, means for admitting pressure fluid to said cylinder for moving said piston against the pressure fluid contained in the cylinder, said last named means being partly under control of said impact responsive tool, a reservoir of pressure fluid in axial alinement with said cylinder and supported

thereby, passages for directing the pressure fluid expelled from said cylinder by movement of the piston into said reservoir, and a compressible element located in said reservoir and adapted to compensate by its volume reduction effected by the incoming fluid, for the increase in fluid volume in said reservoir.

13. In a machine of the character described, the combination of a cylinder, a power piston movable in said cylinder, an auxiliary tubular piston fixedly connected with said cylinder in axial alinement therewith, an impact responsive tool supported by said power piston and movable relatively thereto, a conduit for admitting pressure fluid to the cylinder, a valve for said auxiliary tubular piston supported by said impact responsive tool, and resilient means interposed between said power piston and said impact responsive tool for normally maintaining the latter in predetermined relation to the power piston and for retaining the valve in closing position with respect to said cylinder.

14. In a machine of the character described, the combination of a cylinder, a power piston movable in the cylinder, an auxiliary tubular piston fixedly connected with the power piston, a conduit for admitting pressure fluid to said cylinder, said tubular auxiliary piston being guided in said conduit, a valve normally obstructing flow of pressure fluid through said tubular auxiliary piston, an impact responsive tool slidably carried by the power piston and supporting said valve, whereby, upon impact of said tool, said valve is raised from obstructing position, and a spring interposed between said power piston and said tool for normally retaining said tool in predetermined relation to said power piston.

15. In a machine of the character described, the combination of a cylinder, a power piston movable in said cylinder, a conduit means for admitting pressure fluid to said cylinder, a tubular auxiliary piston fixedly connected to said power piston and movable in said conduit means, an impact responsive tool, an apertured sleeve on the power piston slidably supporting said impact responsive tool, a valve in said auxiliary piston normally obstructing the flow of pressure fluid into the cylinder, the tool supporting sleeve having apertures therein communicating with passages extending through the piston and said impact responsive tool being adapted upon encounter of a movement resisting element, to open the valve and obstruct the apertures through said sleeve, and subsequently to close the passage through said piston.

16. In a machine of the character described, the combination, as set forth in claim 11, in which the compressible and expansible volume compensating element within the reservoir is formed by a hollow, air filled resilient member.

17. In a machine of the character described, the combination, as set forth in claim 11, in which the compressible and expansible volume compensating element within the reservoir is formed by a hollow annular member filled with air.

18. In a machine of the character described, the combination, as set forth in claim 11, in which the compressible, expansible volume compensating element within the reservoir is formed by an annular trough member of V-shaped cross-section and made of resilient material.

ROBERT ALEXANDER CUTHERBERT.
